CLAIM

The ornamental design for a lip product container, as shown and described.

DESCRIPTION

FIG. 1 is a perspective view of an embodiment of a lip product container in an open configuration showing my design;

FIG. 2 is a front elevational view of the lip product container of FIG. 1;

FIG. 3 is a rear elevational view of the lip product container of FIG. 1;

FIG. 4 is a left side elevational view of the lip product container of FIG. 1;

FIG. 5 is a right side elevational view of the lip product container of FIG. 1;

FIG. 6 is a top plan view of the lip product container of FIG. 1; and,

FIG. 7 is a bottom plan view of the lip product container of FIG. 1.

The broken lines illustrate portions of the lip product container and form no part of the claimed design.

The “eos” included on portions of the lip product container depicted in FIGS. 1 and 6 is a registered trademark of eos Products, LLC.
